(57) **CLAIM**

The ornamental design for a teardrop shaped mirror, as shown and described.

DESCRIPTION

FIG. 1 is a perspective view of the teardrop shaped mirror in accordance with the invention, the mirror illustrated mounted on a vehicle;

FIG. 2 is a front elevation view of the teardrop shaped mirror of FIG. 1;

FIG. 3 is a side elevation view of the teardrop shaped mirror of FIG. 1;

FIG. 4 is a right end elevation view of the teardrop shaped mirror of FIG. 1;

FIG. 5 is a left elevation view of the teardrop shaped mirror of FIG. 1; and,

FIG. 6 is a rear view of the teardrop shaped mirror of FIG. 1.

The portions of the vehicle shown in broken lines in FIG. 1 are for illustrative purposes only and form no part of the claimed design.
